DISPENSING CARTON

Marshall L. Williamson, New York, N.Y., and John F. Lee, Paterson, N.J., assignors to Federal Paper Board Company, Inc., Bogota, N.J., a corporation of New York

Filed Jan. 23, 1962, Ser. No. 168,092
8 Claims. (Cl. 221—302)

This invention relates to cartons for dispensing cups, and has for its object the provision of an improved carton and a blank for forming the carton. The invention is concerned primarily with a carton for containing and dispensing drinking cups which are tapered cups having a top rim. The blanks and cartons of the invention are formed of paperboard and are shaped and proportioned to contain a column or stack of cups which are nested together and to releasably hold them for removal one at a time.

The carton of the invention is formed of a single blank, and is multi-sided, preferably of rectangular cross-section, and is relatively long. The cross-sectional dimension is slightly larger than the diameter of the cups and the carton is of such length that it will receive a column or stack of, say, two dozen or more cups in telescopic order. The top of the carton may have any suitable means for holding it in an operable position, advantageously a top closure having means for hanging the carton in an upright position for dispensing the cups.

One important aspect of the carton resides in the construction of the bottom portion which normally supports the stack of cups from the bottom of the lowermost cup but which may be moved to a lower position to hold the stack in dispensing position by the rim of the lowermost cup. The bottom comprises rib means for holding the entire stack merely by the rim of the lowermost cup, which means has such yieldable engagement with the rim that the lowermost cup can be pulled free and the next cup is immediately engaged by its rim and held in position for removal.

The lower portion of the carton comprises cup supporting members formed of folded panels which can be set in an upper position to project into the carton to hold the cups in their upper position but which can be moved to a lower position to form stiff but yieldable ribs extending inwardly from opposite inner sides of the carton. The bottom preferably comprises interconnected closure panels which close the bottom and hold said cup supporting members in their upper position but which may be opened to let the stack slide down to set the cup supporting members in the lower position and the ribs form so that the lowermost cup is held by its rim on the ribs in an exposed position. Advantageously, the bottom closure panels assume a recessed position whereby the walls of the carton terminate in a folded edge on which the carton can rest in an upright position.

The accompanying drawings illustrate an embodiment of the invention in which —

FIG. 1 is a plan view of a blank for the carton;

FIG. 2 is a side elevation, partly in section, of a carton of the invention containing a stack of cups;

FIG. 3 is a view from below of FIG. 2;

FIG. 4 is a view similar to FIG. 3 with the bottom closure panels removed;

FIG. 5 is an enlarged sectional view of the lower portion of the carton of FIG. 2 showing the cups in dispensing position, and

FIGS. 6 and 7 are fragmentary sectional views of the cup supporting members showing different positions of setting up the panels in the erection of the carton.

The blank of the invention illustrated for a carton which is rectangular in cross-section comprises four rec-

2

tangular and elongated panels 1, 2, 3 and 4 interconnected along fold lines 5, 6 and 7, and a glue flap 8 interconnected to panel 4 along fold line 9. These panels form the side walls of the carton of FIGS. 2 to 5. Extending above the fold line 12 are panels consisting of closure flaps 13 and 14 which fold inwardly over each other, and top closure panel 15 having a slit 16 on the fold line 12 and a tuck flap 17 foldable on the fold line 18. The edges of fold line 18 have slits 19 and 20 which, when the carton is closed, make locking engagement with the edges 22 and 23 of the flaps 13 and 14 in what is known as a "shur-lock" engagement. The panel 24 has an intermediate fold line 25 and an end fold line 26 forming two panels 27 and 28, and tuck flap 29. The panels 27 and 28 have holes 32 and 33 respectively which, as shown in FIG. 2, coincide when the panels are folded together to form a hanger for the carton. Any suitable means for holding the carton may be used. When the carton is closed the flap 29 is inserted into the slit 16 to secure the suspending panel 24 in position. When this flap is pulled out of the slit and the folded panel 24 is erected as in FIG. 2, the holes 32 and 33 can be used to hang the carton on a hook.

The bottom of the blank and especially the panels 2 and 4 have cup supporting members 35 and 36 foldable along lines 44 and 45 respectively. These members have glue flaps 39 and 40 foldable along lines 42 and 43 respectively. The fold lines 44 and 45 are substantially in line with slightly U-shaped cuts 46 and 47. These fold lines and cuts divide members 35 and 36 into intermediate panels 48 and 49, and 50 and 51 respectively. Panels 49 and 51 are further divided along slotted fold lines 52, 53 and 54, 55 to form the narrow rib panels 56 and 57 respectively. This construction also divides panels 49 and 51 to form panels 49a and 51a between fold lines 44 and 52 and 45 and 54 respectively. The fold lines 52 and 54 have three slits each which make them weaker and easier to break than fold lines 53 and 55 which have only two slits each. (The importance of these slotted fold lines will be described later.)

The panels 1 and 3 have bottom closure panels 60 and 61 which are foldable along the nicked lines 62 and 63. These panels have fold lines 64 and 65 connected with U-shaped cuts 66 and 67 which divide the panels 60 and 61 into two panels 68, 69 and 70, 71 respectively.

The panels 69 and 71 have integral ears 75, 76 and 77, and 78, 79 and 80 respectively the function of which will be described later.

In forming the carton of the invention in the plant of the blank manufacturer, the blank of FIG. 1 is passed through a gluing operation to apply glue to the underside of flap 8 and the upper surfaces of flaps 39 and 40 as viewed in FIG. 1. Then cup supporting members 35 and 36 are folded along score lines 44 and 45 and flaps 39 and 40 are glued to panels 2 and 4 respectively. Then panel 4 is folded along score line 7 to a flat position over panel 3. Then panel 1 is folded along score line 5 and into bonding contact with the glue on flap 8. The cup supporting members 35 and 36 are tapered to facilitate folding panels 4 and 1. The carton as thus formed is semi-erected and may be shipped in this form to a manufacturer of cups who completes the carton erection and packaging of the cups.

The erected carton of FIGS. 2-5 is formed by pushing the panels 1, 2, 3 and 4 so as to give the carton the square cross-section shown in FIGS. 2-5. The stack of cups may be inserted and then the top is closed by folding panels 13 and 14 inward with panel 14 over panel 13, then panel 15 over panel 14 and tucking in flap 17 so that the edges 22 and 23 engage the slits 19 and 20. The hanger 24 is folded over panel 15 and the flap 29 is inserted into slit 16 and the top is closed. When the carton

is to be suspended for use, the hanger is pulled to an upright position, folded over on itself with the flap 29 inserted into the carton along panel 1 as shown in FIG. 2. The two holes 32 and 33 coincide and this gives a reinforced hanger. The carton may also be held in upright dispensing position by glue, a bracket or other means.

The positions of the cup supporting members of FIG. 2 are attained from the semi-erected carton as follows: From the flat position of the cup supporting members 35 and 36, after gluing the flaps 39 and 40, they are lifted to the position of FIG. 6 and pressure is applied mechanically in the direction of the arrow which, because of the weak fold lines 52 and 54, causes the panels to break along these lines as shown in FIG. 7 and not along lines 53 and 55. On further pushing the panels break along the less weakened fold lines 53 and 55 as shown in FIG. 7. This permits the cup supporting members to assume the position shown in FIG. 2. If lines 52 and 54 were not weaker than lines 53 and 55 this sequence of folding could not be achieved mechanically in any practical operation.

FIG. 2 shows that the cup supporting members 35 and 36 can assume an upper position which supports the column of cups C from the bottom of the lowermost cup. Various means may be used to hold the members in this position, such as the preferred bottom closure shown. When the members are in this position the bottom closure 60 is pushed inwardly into bearing contact with panels 49a and 51a of the members 35 and 36 respectively until the ears 75 and 77 snap into the slits 46 and 47. Then panel 71 is pushed inwardly over panel 69 until the ears 78 and 80 also snap into position in the slits 46 and 47. Since panel 69 underlies panel 71 and also has the slit 66, the ear 79 of panel 71 snaps into this slit 66. In this case ear 76 has no function, but it will snap into slit 67 if panel 71 is first folded in with panel 69 thereover. It will be apparent from the construction of the various members forming the bottom closure that panel 71 is identical with panel 69 and could be folded into position ahead of panel 69 rather than after it. It will be noted with reference to FIGS. 2, 4 and 5 that the panels 68 and 70 of the bottom closures slope upwardly at a sharp angle and that the panels 48 and 50 of the cup supporting members 35 and 36 also slope upwardly at the same angle with the result that the closed bottom is appreciably above the lower folded edges of the carton which extend along the nicked lines 62 and 63 and the fold lines 37 and 38. The carton accordingly can rest in a stable position on these four edges since the bottom is held in an upward or concave position.

When it is desired to use the carton for dispensing the cups the carton is held upright or suspended from the hanger 24 and the edge of the carton along fold line 63 is pushed outwardly to release the ear 76. Then the edges of the carton along fold lines 37 and 38 are pushed outwardly to free the ears 75 and 77 and 78 and 80 to permit the column of cups to fall to the position shown in FIG. 5. The bottom closures no longer perform any utility and can be removed by tearing them off along the nicked lines 62 and 63.

When the bottom closure panels have been released as aforementioned the weight of the column of cups forces the cup supporting members 35 and 36 to move downwardly from the position shown in FIG. 2 to the position shown in FIG. 5. As shown in FIG. 5 there are then three thicknesses of material which offer resistance to the spreading apart of the carton by reason of the rims R sliding downwardly along the inclined surfaces of the panels 49 and 51. The narrow panels 56 and 57 are bent along the slit weakened lines 52, 53 and 54, 55 respectively, whereby the angles formed between panels 49a and 56, between 51a and 57, between 56 and 49 and between 57 and 51 are relatively sharp making rib panels 56 and 57 relatively stiff and well defined whereas otherwise they would be rounded and soft.

As a result of this construction of the cup supporting

members 35 and 36 they support the entire column of cups without weakening and dropping them. However, they have sufficient resiliency to yield when the lowermost cup is pulled downwardly and to spring back and still firmly support the remaining cups on the ribs 56 and 57 which immediately engage the rim of the next lowermost cup.

The invention has been described and illustrated in an advantageous embodiment having four sides; however, the carton of the invention may be hexagonal or octagonal in cross-section in which cases also there are one or more cup supporting members.

In the preferred embodiment of the invention illustrated there are two cup supporting members facing each other on opposite sides. In another embodiment of the invention, the cup supporting member on one side may be omitted by shaping or proportioning the one cup supporting member to have such stiffness that it will hold the stack of cups and release them as described above. In still another variation of the invention one cup supporting member as illustrated may be used on one side and on the opposite any suitable obstruction to the free movement or release of the cup rim may be provided, such as a notch, ridge or attached sheet of paperboard.

We claim:

1. A carton for containing and dispensing cups of the type which have top rims and can be nested together in stacks which comprises a structure formed within its side walls for receiving a stack of cups, at least two of the opposite side walls having panels folded to form stiff but yieldable cup supporting members extending from opposite side walls into the carton, said members each being formed of a plurality of panels and a glue flap, one of the panels being foldable along a score line between the panel and the side panel and with the glue flap glued to the inside of the side panel in such a position that the remaining panels are angularly bent along score lines so as to form cup supporting projections which can be pulled downwardly to form projecting ribs which bear against the top sides of the cups and engage and hold the entire stack by the rim of the lowermost cup.

2. A carton as defined in claim 1 which comprises a removable bottom closure for the carton having projecting ears which enter slits in the panels of the cup supporting members for holding the cup supporting members in an upper position to support the cups when the bottom is closed, the cup supporting members being movable to a lower cup-supporting position when the bottom is opened.

3. A carton as defined in claim 1 in which one of said panels is relatively narrow and bent along slotted score lines at sharp angles to form a well defined relatively stiff rib.

4. A carton for dispensing cups of a type which have top rims and tapered to nest together in a column, four side walls forming an elongated receptacle of substantially square cross-section, means for holding the carton in an upright position with the bottom free, two of the opposite side walls having integral panels folded inwardly to form inwardly projecting and resilient cup supporting members which engage and hold the rim of the lowermost cup, each member having a plurality of panels folded along score lines including a flap secured to the inside of its wall and a narrow panel which is sharply bent from its adjoining panels to form a rib of such stiffness that it will hold the column of cups but will yield to permit removal of the lowermost cup, the cup supporting members being movable to an upper position to hold the cups when the carton bottom is closed and to a lower position to engage the rims when the carton is used for dispensing the cups, a carton bottom closure having a hinged member on each of two opposite side walls, each hinged member having a nicked line to facilitate its removal when the closure is opened, and a projecting ear on each hinged member for engaging a slot in a side panel to hold the bottom closure in closed position.

5. A carton as defined in claim 4 in which the bottom panels are pushed inwardly to a locked position leaving edges formed along fold lines on which the carton can be set in an upright position.

6. A carton as defined in claim 4 which comprises cup supporting members each having four panels and a glue flap glued to the inside of its wall, said members being movable to an upper position to project into the carton to support the cups when the closure is closed and movable to a lower position to engage the rims and hold the cups in the dispensing position.

7. A carton for dispensing cups of a type which have top rims and tapered to nest together in a column, four side walls forming an elongated receptacle of substantially square cross-section, means for holding the carton in an upright position with the bottom free, two of the opposite side walls having integral panels folded inwardly to form inwardly projecting and resilient cup supporting members which engage and hold the rim of the lowermost cup, each cup supporting member consisting of four panels one of which is a rib panel and one a glue flap all on one side wall, said panels being folded inwardly and the glue flap

glued to the inside of its side wall, the rib panel being narrow and formed between slotted fold lines to give a sharp angle of bend which gives the rib such stiffness that it will hold the column of cups but will yield to permit removal of the lowermost cup, the cup supporting members being movable to an upper position to hold the cups when the carton is closed and to a lower position to engage the cup rims when the carton is used for dispensing the cups, and an openable closure for the bottom of the carton which holds the cup supporting members in their upward position to support the column and when the closure is opened lets the cup supporting members fall to a position to engage the rims of the cups.

8. A carton as defined in claim 7 consisting of a single blank formed so that the grain of the paperboard runs in the longitudinal direction of the ribs.
